UNITED STATES PATENT OFFICE

154,580

DESIGN FOR A BOOK END

Warner Austin, San Diego, and Robert H. Burgert,
Alpine, Calif.; said Austin assignor to said
Burgert

Application December 14, 1946, Serial No. 135,527

Term of patent 14 years

(Cl. D33—1)

To all whom it may concern:

Be it known that Warner Austin and Robert H. Burgert, citizens of the United States of America, residing at San Diego and Alpine, respectively in the county of San Diego and State of California, have invented a new, original, and ornamental Design for a Book End, of which the following is a specification, reference being had to the accompanying drawing, forming a part thereof.

The figure of the drawing is a perspective view of our new design for a book end

We claim:

The ornamental design for a book end, substantially as shown.

WARNER AUSTIN.
ROBERT H. BURGERT.
